UNITED STATES PATENT OFFICE.

SERGIUS VERNET, OF SYRACUSE, NEW YORK, ASSIGNOR TO H. H. FRANKLIN MANUFACTURING COMPANY, OF SYRACUSE, NEW YORK, A CORPORATION OF NEW YORK.

PRIMER FOR INTERNAL-COMBUSTION ENGINES.

Application filed May 25, 1921. Serial No. 472,468.

To all whom it may concern:

Be it known that I, SERGIUS VERNET, a citizen of the United States, residing at Syracuse, in the county of Onondaga and 5 State of New York, have invented a certain new and useful Primer for Internal-Combustion Engines, of which the following is a specification.

This invention relates to primers for internal combustion engines and has for its object a particularly simple and efficient controlling means for such primer.

The invention consists in the novel features and in the combinations and constructions hereinafter set forth and claimed.

In describing this invention, reference is had to the accompanying drawings in which like characters designate corresponding parts in all the views.

20 The figure is a fragmentary view of a carburetor embodying my invention, the primer being shown, partly in section, and partly broken away, and the electric circuits being also shown diagrammatically.

25 This primer comprises generally, a chamber having an inlet communicating with a fuel supply reservoir as the fuel or float chamber of the carburetor, also one or more air inlets, a gas outlet, an electrical heating unit in the chamber, electromagnetic means for opening the valve, an electric circuit having branches connected to the heating unit and to the electromagnetic means, and a switch for opening and closing the circuit.

30 The gas outlet communicates with the outlet of the carburetor above the throttle valve.

I have here illustrated the primer as forming part of the carburetor.

35 1 designates the chamber of the primer which is here shown as mounted or cast on the side of the carburetor 2. The chamber is formed with a fuel inlet 3 near one end which communicates with a suitable passage leading to the interior of the carburetor or 40 the float chamber thereof and with a gas outlet 4 communicating with a passage 5 leading into the outlet 6 of the carburetor above the throttle valve 7.

45 The chamber 1 is also provided with one or more air inlets, it being here shown as provided with an inlet 8, 9 near its opposite ends. The chamber 1 is here shown as extending in a general horizontal direction but inclined slightly toward its receiving end 50 downwardly out of the horizontal. The gas

outlet 4 leads from the upper end portion of the chamber and opens through the upper face of a block 1^a mounted on or cast on the carburetor in which block the passage is formed.

55 10 is a reciprocally movable valve controlling the flow through the gas outlet 4 and seating at 11 in the outlet. This valve projects upwardly out of the passage and is provided with an iron extension 12 which constitutes the armature of the electromagnetic means for lifting the valve 10 from its seat. A spring as 13 is provided for normally holding the valve against its seat and from opening by suction.

60 14 is a heating unit or coil suitably mounted in the chamber 1 and having terminals 15, 16 at the opposite ends of the chamber.

65 17 are the coils of an electromagnet here shown as mounted in alignment with the valve 10 so that the armature 12 constitutes the core of the magnet coils.

70 The spring 13 encircles a rod 18 extending from the core 12 coaxially of the coils 17 and projecting through the head or disk 19 at the upper end of the coils, the spring thrusting against the inner side of the head 19 and against the upper end of the core 12.

75 The coils 17 are connected in series or in shunt in an electric circuit which is controlled by a switch 20. When the switch is closed, the current passes through the heating coil and through the magnet coils.

80 When starting the throttle valve is preferably first closed, then the switch 20 is closed to energize the heating unit, and the electro-magnet. Also, the starting motor of the engine is started. When the starting 85 motor turns over the engine, the fuel is drawn into the chamber 1 and heated, vaporized and mixed with air to form a combustible gas and the gas formed passes through the outlet of the carburetor above 90 the throttle and into the manifold.

95 Upon opening of the switch 20, the valve 12 is closed by the spring 13 and the heating unit cut out. As here illustrated, the electro-magnet coils are connected in shunt with the heating unit, the terminals 15, 16 of the heating unit being connected to the switch terminals by the wires 22, 23 and the magnet coils being connected in shunt with the terminals 15 and 16 of the heating coil by 100 105 110

wires 24, one of which is grounded at 25.
What I claim is:

A primer for internal combustion engines comprising a heating chamber extending in a general horizontal direction and a heating element extending lengthwise of the horizontal chamber, said chamber having a fuel inlet and an air inlet at one end of the chamber near one end of the heating element and an air inlet and a gas outlet at

the other end of the chamber and near the other end of the heating element and means for controlling the flow of the mixture out of the chamber.

In testimony whereof, I have hereunto signed my name at Syracuse, in the county of Onondaga, and State of New York, this 24th day of May, 1921.

SERGIUS VERNET.
